COMBINED DECANTER AND CLOSURE
THEREFORWalter T. Heintze, New Canaan, Conn., assignor to Schenley Industries, Inc., New York, N.Y., a corporation of Delaware

Filed Sept. 20, 1967, Ser. No. 8,673

Term of patent 14 years

Int. Cl. D9—01

U.S. Cl. D9—145

FIGURE 1 is an elevational view of a combined decanter and closure therefor embodying my new design, the side opposite being identical in appearance with the side illustrated;

I claim:

The ornamental design for a combined decanter and closure therefor, as shown and described.
